UNITED STATES PATENT OFFICE.

CHARLES EDWARD HAVILAND, OF PARIS, FRANCE.

DESIGN FOR A COVERED DISH OR SIMILAR ARTICLE.

40,520.

Specification for Design.

Patented Feb. 22, 1910.

Application filed December 16, 1909. Serial No. 533,485. Term of patent 14 years.

To all whom it may concern:

Be it known that I, CHARLES EDWARD HAVILAND, a citizen of the United States, residing at Paris, France, have invented a new, original, and ornamental Design for a Covered Dish or Similar Article, of which the following is a specification, reference being had to the accompanying drawings, forming part thereof, and in which—

dish embodying my design; Fig. 2 a side elevation of the same, and Fig. 3 an end elevation of the same.

I claim:

The ornamental design for a covered dish or similar article, as shown.

CHARLES EDWARD HAVILAND.
